UNITED STATES PATENT OFFICE.

FRANK McLAUGHLIN, OF PHILADELPHIA, PENNSYLVANIA, ASSIGNOR, BY MESNE ASSIGNMENTS, TO INTERNATIONAL WINDOW MANUFACTURING COMPANY, OF DOVER, DELAWARE, A CORPORATION OF DELAWARE.

LOCK FOR PIVOTED WINDOWS.

1,073,268.

Specification of Letters Patent. Patented Sept. 16, 1913.

Application filed January 3, 1912. Serial No. 669,170.

To all whom it may concern:

Be it known that I, FRANK McLAUGHLIN, a citizen of the United States, residing in Philadelphia, Pennsylvania, have invented 5 certain Improvements in Locks for Pivoted Windows, of which the following is a specification.

One object of my invention is to provide a novel form of device whereby a pivoted 10 window sash may be retained either in its normal closed position or in any of a number of open positions in which it is inclined at an angle to the plane of the window frame; the arrangement of parts being such 15 that the sash may be moved to a partially open position and held therein so as to permit of the entrance of greater or less amount of air, as may be desired.

Another object of my invention is to provide 20 a locking or holding device for a pivoted window, with means whereby it may be operated from the inside of a room in whose wall the window sash is mounted.

The invention further contemplates such 25 a construction of the holding device as will permit of its automatic adjustment as the window sash is turned to various angles, and which will include a cover for the recess in which one of its parts operates; the 30 arrangement being such that the cover shall be movable by such part and shall effectually prevent the entrance of air or solid material into the interior of the window sill structure.

35 A further object of the invention is to provide a novel form of sash holding device particularly adapted for use in connection with pivoted windows and made in two parts, of which one is carried by the 40 sill and the other by the window sash; the arrangement being such that the two parts are locked together as long as the window occupies an inclined position, but are detached so as to permit of vertical movement 45 of the window sash when the latter lies in or is brought to a substantially vertical plane.

These objects and other advantageous ends I secure as hereinafter set forth, reference being had to the accompanying drawings, in which:—

Figure 1 is a front view illustrating my invention as applied to a lower window sash; Figs. 2 and 3, are vertical sections, of

which the first illustrates a window sash as 55 lying in a substantially vertical plane and the second illustrates the sash as locked in an inclined position; Fig. 4, is a perspective view of the main casting forming part of that portion of the invention mounted in 60 a window sill; Fig. 5, is a perspective view of the locking slide which is operative in the structure shown in Fig. 4, and Fig. 6, is a perspective view of that portion of the device which is mounted on the window 65 sash.

In the above drawings, 1 represents a portion of a window sill, and 2 is the body of a window sash having a pivot 3 connecting one side of its lower portion to one of a pair 70 of slides 4; it being understood that a second slide is similarly pivoted to the opposite side of said body. These slides, as is well understood in the art, are free to move vertically in the guideways of the window 75 frame and the arrangement is such that the body of the sash is free to turn on its pivots from the position shown in Fig. 2 to that shown in Fig. 3.

The window sill structure is recessed for 80 the reception of a casting 5 (Fig. 4) which consists of a supporting framework formed of an angle piece 6 having a downwardly extending hollow guideway 7. In this guideway is mounted a slidable member 8 85 having an abutment 9 whereby its downward movement in the guideway 7 is limited and provided at its upper end with a transverse slot 10 whose section is that of an inverted T. Said member 8 is hollow and 90 has centrally mounted in suitable holes a longitudinally movable locking pin 11. On this latter is mounted a spring 12 which is confined between a collar 14 on the upper end of the pin and a transverse ledge 13; 95 the arrangement being such that the pin is normally retained in an extended position at the upper end of the member 8 within the slot 10. Said member 8 is normally held with its abutment 9 against the edge 100 15 of the structure 5, by a spring 16 shown in Figs. 2 and 3; and is free to move upwardly from this position for a limited distance.

Mounted on the lower member of the 105 window sash, is a plate 18 held in place by screws and having formed integral with it a second plate 19 projecting in a plane at

right angles to the plane of the sash and preferably having a circularly curved outline. The outer edge of this curved plate has mounted upon it a circularly curved flange 20 whose transverse lines lie in planes substantially parallel to the plane of the plate 18, and as shown in Fig. 6, it terminates at such a point as to clear the adjacent face of the member 8 when the sash is in its normal position. This flange has formed in it a number of holes 21 which extend in lines substantially radial to its center of curvature. The proportions of the plate 19 and its flange 20 are such that they snugly fit the T-shaped slot 10 of the slide 8, although the curve of said flange, is not in this case concentric with the line of the pivots 3.

Hinged to the rear top edge of the part 6 is a cover plate 22 so placed that under operating conditions it is free to be moved by the sash as this is turned on its pivot from the position shown in Fig. 2 to that shown in Fig. 3. When said sash is in its normal position this plate is held by a small spring 23 in the closed position, thereby preventing the entrance of air, water or foreign material into the casting 5.

For operating the pin 11 I provide a bell crank lever 24 set in a suitable recess of the window frame and pivoted thereto at 25. One arm of this lever is connected to the lower end of the locking pin 11, while its opposite end is attached to a rod 26 guided in a bushing 27 set in the window sill and provided with a head 28.

With the above described arrangement of parts, the window sash, when in its normal position, is free to be moved up or down, since the flange 20 of the plate 18 does not, under these conditions, enter the slot 10, although it is held from swinging on the pivot 3 by reason of the fact that the locking pin 11 enters one of the holes 21 in the curved plate 20.

When it is desired to open the window without raising it, the locking pin 11 is pulled downwardly out of engagement with the plate 20 by pressing inwardly on the head 28, which communicates such motion to the pin through the bell crank lever, in opposition to the spring 12. As soon as the pin 11 has been withdrawn, the sash may be turned on its pivots 3 to the desired angle and thereafter the releasing of the pressure on the head 28 will permit the locking pin, under the action of the spring 12 on its collar 14, to be forced into one of the holes 21, thus locking the sash in the given inclined position. The turning the sash on its pivot not only enters the flanged plate 19 in the slot 10, but causes said plate to raise the cover plate 22 and in addition pulls upwardly the slide 8 in the casting 7 against the action of the spring 15. While the sash

is in the vertical position, it may be moved in the window frame although by reason of the T-shaped structure formed by the flanged plate 19, it is locked to the window sill after being moved from the vertical position sufficiently to cause the lower end of the plate 19 to enter the slot 10 in the top of the member 8. This T slot is longitudinally curved to accommodate the curved plate 19 and its flange, 20 and inasmuch as the slideable member 8 is held to the casting 5 both by its spring 16 and the arm of the bell crank lever 24, the sash is effectually locked by my device against vertical movement as long as it is inclined.

If the push rod 26-28 be located on the inside of the window frame, it is obvious that when the sash is inclined from the vertical position it cannot be unlocked from the outside, so that the window, although open to permit of ventilation, is effectually held so that it cannot be raised or further opened to effect an entry.

I claim:

1. The combination of a window frame; a sash including slides and a body pivoted thereto; a flanged element mounted on one of the two members comprised by the frame and the sash, and a slotted element for the reception of said flanged element mounted on the other of said members; with a device for locking the flanged element in any of a number of positions in engagement with the slotted element.

2. The combination of a window frame; a sash mounted in the frame and consisting of slides with a body pivoted thereto; a slotted member mounted in the window frame adjacent to the lower portion of the sash; a flanged member carried by the sash and capable of entering the slotted member when the sash body is turned on its pivots; with a locking pin mounted in the slotted member for holding the sash in any of a number of inclined positions.

3. The combination of a window frame; a window sash mounted in the frame and consisting of slides with a body pivotally connected thereto; a vertically slideable slotted structure mounted in the frame adjacent one end of the sash; a spring normally holding said structure in a retracted position; a spring-actuated locking-pin carried by said structure; and a flanged member mounted on the window sash in position to enter the slot of the structure on the window frame and having a series of openings for the reception of the locking pin.

4. The combination of a window frame; a window sash mounted in the frame and consisting of slides with a body pivotally connected thereto; a vertically slideable slotted structure mounted in the frame adjacent one end of the sash; a spring normally holding said structure in a retracted posi-

tion; a spring-actuated locking-pin carried by said structure; a flanged member mounted on the window sash in position to enter the slot of the structure on the window frame and having a series of openings for the reception of the locking pin; with a hand-operated device for withdrawing the pin from engagement with the flanged member.

5 5. The combination of a window frame having a slotted member mounted in a recess below the top surface of its sill; a sash slidably mounted in the frame and consisting of a pair of slides with a body pivoted thereto; a flanged member mounted on the lower portion of the sash and projecting into the recess in the sill when said sash is in its closed position; a cover for a portion of the recess, mounted to be moved by the sash 15 when the latter is swung on its pivots; and means for holding the sash in any position inclined to the vertical.

20 6. The combination of a window frame; a sash slidably mounted in the frame and

consisting of a pair of slides with a body 25 pivoted thereto; a curved plate mounted on the sash body with its center line to one side of the line of the pivots and provided with a laterally projecting flange having openings; a guide structure mounted in the window frame; a slideable member mounted in said structure and provided with an undercut slot for the reception of the flange of said plate on the sash; a spring-actuated locking-pin mounted on the slideable member 30 in position to enter any of a number of openings in the flanged plate of the sash; a spring placed to resist movement of the slideable member; and a hand-operated device for actuating the said pin. 35

In testimony whereof, I have signed my name to this specification, in the presence of two subscribing witnesses.

FRANK McLAUGHLIN.
